FIFTHS TO SAID WOODSON.

LIQUID-FILTER.

1,274,227.

Specification of Letters Patent.

Patented July 30, 1918.

Application filed April 6, 1916. Serial No. 89,420.

To all whom it may concern:

Be it known that I, JOHN M. WOODSON and JOE H. WILDER, citizens of the United States, residing at Lafollette, in the county 5 of Campbell and State of Tennessee, have invented certain new and useful Improvements in Liquid-Filters, of which the following is a specification.

This invention relates to filters, and more 10 particularly appertains to an improved water filter.

The primary object of the invention is to provide a filter of the character described, which may be attached to cisterns, water 15 hydrants, or may be used in conjunction with water plants.

Another object of the present invention resides in the construction of the receiving chamber, which chamber is so constructed 20 from a plurality of sections, the same being so assembled as to provide for a device readily accessible for cleaning and the like.

The invention contemplates the provision 25 of a sectional water receiving chamber, the said chamber being provided with several tubular like portions which are adapted to be connected with suitable inlet and outlet means. These tubular like portions communicate with an enlarged base portion 30 which serves as a settling chamber, that is, allowing that foreign matter as contained by the water to be deposited therein due to the decreased pressure of the water as it enters the same.

35 The invention also contemplates the provision of a suitable filtering substance, which substance is contained within one of the tubular portions, adjacent the outlet.

We have illustrated the above mentioned 40 embodiment of the invention in the accompanying drawing forming a part thereof, and improved details in the construction and arrangement of parts will be apparent from an inspection of such drawings in connection 45 with the specific description hereinafter contained.

In the drawings:—

Figure 1 is a longitudinal section of the filter; and

50 Fig. 2 is a transverse section taken on the line 2—2 of Fig. 1.

Referring now more specifically to the drawings wherein like reference characters designate like or corresponding parts 55 throughout the several views, and in which

1 represents an enlarged base portion, provided with interiorly threaded openings 2 and 3, and a centrally arranged convex deflector 4, which serves as suitable means for deflecting the course of the water flow. The 60 base portion 1, or as it may be termed, the settling tank, may be provided with a drain valve 5, which is threadedly secured within a suitable opening 6 formed in the lower portion of chamber 1. Supported within the 65 threaded openings 2 and 3, are tubular members 7 and 8, the same being provided exteriorly with complementally arranged threaded portions for engagement therewith. The upper ends of the tubular members 7 and 8 are normally adapted to receive heads 70 9 and 10, the same being threaded into engagement therewith as at 11 and 12, while upon the top faces thereof are arranged octagonal members 13, which are adapted to 75 be engaged by some suitable turning implement whereby they may be threaded into the upper ends of said tubular members. The head 9 is provided with a vertical interiorly 80 threaded bore 14 arranged concentrically thereof, which bore is adapted to have turned into engagement therewith a threaded conduit or pipe 15, thus providing a suitable inlet means. The head 10 normally serves as an efficient closure for the upper end of the 85 tubular member 8. The tubular member 8 is provided with an outlet nipple 15^a, which may be formed integrally therewith, as illustrated in the drawing, or may be a detachable member, such as conditions or preferences may dictate. This nipple 15^a is provided with an interiorly threaded portion 90 16, which portion is adapted to have turned into engagement therewith, a pipe 17. We preferably arrange the nipple upon one side 95 of the tubular member at a point adjacent its upper end, the purpose of which shall be subsequently apparent. In order to provide for means whereby the tubular members 7 and 8 may be rigidly held in their vertical 100 positions, bracket arms 18 and 19 are formed on the member 8, which brackets have circular yoke members 20 and 21 formed thereon. The yoke members embrace the tubular member 7 and thereby, serve as efficient means 105 for the above mentioned purpose and also, to secure the said tubular members in such a manner as to be relatively immovable laterally.

Positioned adjacent the lower end of the 110

tubular member 8, and carried by the outlet 3 of the settling chamber 1, is a screen member 22 which serves as efficient means for supporting a suitable filtering material designated at 23. The filtering material may be charcoal, or other similar substance, well known to this particular art. In placing this filtering material 23 within the tubular member 8, the cap or head 10 is removed 10 from the upper end of the said tubular member, whereupon the filtering material may be readily deposited therein, until the same reaches a point adjacent or slightly below the nipple portion 15^a. After the charcoal 15 or filtering material has been placed within the tubular member, the head 10 may be then replaced upon the said member and will of course be ready for its filtering operation. In reduction to practice, it will be noted 20 that the water is introduced into the tubular member 7 by means of the pipe 15, whereupon it flows downwardly into the settling chamber 1, which due to its increase of size will cause the velocity of the water to be somewhat diminished, thereby allowing a 25 portion of the foreign matter to settle to the bottom of the chamber 1. The water in its continued flow passes through the screen 22 and the filtering material 23, whereupon the 30 water is purified. The water then passes from the tubular member 8 out of the distributing pipe 17, whereupon it may be used for various purposes. At certain intervals, the valve 5 arranged in the chamber 1 may 35 be opened, to allow the sediment collected therewithin to be removed. It is to be noted also that the convex portion 4, serves to a certain extent as a baffle or deflector, preventing the immediate passage of the water 40 from the tubular member 7 into the tubular member 8, and causing the water to be deflected downwardly. In instances where it

is desirable to remove the tubular members 7 and 8 from the settling chamber 1, it will be obvious that it is only necessary to first 45 remove the member 7, whereupon the member 8 may be also readily disengaged, thereby allowing access to be had to said settling chamber. We also direct attention to the fact that although we have illustrated the 50 bracket arms 18 and 19 as being formed integral with the tubular member 8, the same may be readily separate and distinct elements.

While we have herein disclosed a specific 55 embodiment of the invention, it will be apparent to persons skilled in this particular art that the invention is capable of embodying other forms and devices differing in detail and arrangement from that shown, as 60 may be in keeping with the appended claim.

We claim:

A liquid filter, including a receiver having companion openings with shouldered filter pipe recesses, the top of the receiver being 65 depressed to form a deflector between the companion openings, an inlet filter tube disposed in one of the shouldered recesses, a filtering screen supported in the other of the shouldered recesses, an outlet filter tube 70 arranged in said shouldered recess whereby the screen is clamped in position, bracket arms formed on the outlet filter tube, said bracket arms having yoke members for encircling the inlet filter tube and mutually 75 supporting both filter tubes, and a filtering substance supported by the filtering screen.

In testimony whereof we affix our signatures in presence of two witnesses.

JOHN M. WOODSON.
JOE H. WILDER.
